UNITED STATES PATENT OFFICE.

ERNEST BUTLER, OF GERBER, CALIFORNIA.

CLOTHES DRIER.

Application filed November 3, 1921. Serial No. 512,586.

To all whom it may concern:

Be it known that I, ERNEST BUTLER, a citizen of the United States, residing at Gerber, in the county of Tehama and State of California, have invented certain new and useful Improvements in Clothes Driers; and I do declare the following to be a full, clear, and exact description of the invention, such as will enable others skilled in the art to which

10 it appertains to make and use the same.

This invention relates to an improved clothes drier and one object of the invention is to provide a drier having an improved construction of standard, the standard including telescoping sections, the inner one of which is provided with a longitudinally extending groove or seat for receiving a hoisting line or cable and also receiving the inner end portion of a fastener for a bracket carrying a drum upon which the cable is wound, this fastener by extending into the groove or seat serving to hold the inner section of the standard against rotary movement.

25 Another object of the invention is to provide a clothes drier in which the upper section of the standard may be very easily moved upwardly and securely retained in the elevated position.

30 Another object of the invention is to provide a clothes drier in which the sections of the standard may be always moved very easily, these sections being formed of tubular metal and thus not liable to be held 35 against sliding as would be the case if they were formed of wood or other material which could expand when wet.

Another object of the invention is to provide a clothes drier in which the line-carrying arms may be connected with the upper end portion of the upper standard section in a very efficient manner and securely held in place but permitted of easy removal when desired.

45 This invention is illustrated in the accompanying drawing; wherein:

Figure 1 is a view showing the improved clothes drier in side elevation with the line carrying arm broken off.

50 Figure 2 is a view similar to Fig. 1 taken at right angles thereto.

Figure 3 is a view showing the improved clothes drier in vertical section.

55 This improved clothes drier is provided with a standard or mast having a lower tubular section 1 which is to be embedded

in the ground or in any suitable foundation or support. The upper section 2 of this standard is also formed of metal tubing and slidably fits into the lower section 1. This upper section 2 is provided with a longitudinally extending depression which forms a groove or seat 3, the lower end of which communicates with an opening 4 through which will pass a line or cable 5. This line or cable 5 is connected with a cross bar 6 which extends through the lower end portion of the section 2 and after being carried upwardly through the groove or seat 3 is passed outwardly through the opening 7 and wound upon the drum shaft 8 between the disk 9 and ratchet disk or wheel 10. This drum shaft 8 is rotatably carried by the bearing brackets 11 which are riveted to the collars 12 and one of these brackets is provided with an arm extension 13 having a pawl 14 pivotally connected therewith and normally resting in engagement with the ratchet wheel 10. A pin or handle 15 extends from this pawl so that the pawl may be easily swung upwardly out of engagement with the ratchet wheel thus permitting the drum shaft to be rotated when it is desired to lower the upper section 2 of the standard. Ordinarily the pawl rests as shown in Fig. 1 and it will be readily seen that when the drum shaft is turned by means of the handle 16 to raise the section 2 of the standard, the pawl will prevent reverse rotation of this ratchet wheel. From an inspection of Fig. 3, it will be seen that the collars are provided with securing screws 17 which pass through aligned openings formed in the collars and lower post section 1 and serve to assist the bolts 18 in holding the collars in place upon the standard. From an inspection of this figure, it will also be seen that one of these securing screws 17 extends into the depression or seat 3 and will thus serve to prevent the upper section 2 of the standard from having rotary movement. It will be further noted that with this elongated screw in place, the upper section cannot become disconnected from the lower section due to the fact that this lower section is forced outwardly at the lower edge of the opening 4 thus providing a spur 19 which would engage the inner end of the securing screw and prevent entire removal of the upper section 2 from the lower section 1. The seat or depression 3 thus serves the double function of providing a seat for the

line and of providing a keyway to receive the securing screw which serves to prevent rotary movement of the upper standard section and also serves to prevent entire removal of the upper section from the lower section.

The upper section 2 is provided with a head 20 which fits into the upper section and is provided with an outstanding collar 10 21 to rest upon the upper end of the section 2 as shown in Fig. 3. This head 20 is provided with an upstanding neck or upper end portion 22 in which will be formed a threaded socket 23 to receive a bolt 24 which serves 15 to retain a cap 25 upon the neck 22. This cap 25 is provided with an outstanding base portion 26 which rests upon the collar 21 and thus provides a good support for the cap. This cap is provided with side openings 20 in which are mounted sleeves 27, the sleeves being secured in place by fastener pins 28 and having openings 29. The bars 30 which are to carry the clothes line will fit into these sockets 27 and the pins 28 in 25 addition to securing the sockets, will also serve to limit inward movement of these arms or bars. It will thus be seen that the arms or bars can be easily inserted or removed when desired.

I claim:

1. In a clothes drier, a standard having a tubular lower section and an upper section slidably fitting into the lower section, the upper section having a longitudinally extending depression forming a cable seat and the lower section having an opening registering with the depression, a drum support carried by said lower section, a drum rotatably carried by said support, a cable extending through the opening of the lower section and having its outer end portion wound upon the drum and its inner end portion positioned in the cable seat of the upper section and connected with the lower end portion of the upper section, and a fastener 40 extending through the drum support and lower section into the cable seat of the upper section to hold the upper section against rotary movement.

2. The structure of claim 1 having the upper standard section tubular and having an opening at the lower end of the cable seat, the inner end of the cable being passed through said opening and anchored within the lower end portion of the upper section. 45

In testimony whereof I have hereunto set my hand.

ERNEST BUTLER.
